UNITED STATES PATENT OFFICE.

DE WILL G. VAUGHN, OF RICHMOND, VIRGINIA, ASSIGNOR OF ONE-HALF TO DALLAS A. SHAFFER, OF RICHMOND, VIRGINIA.

VALVE-GRINDING DEVICE.

1,010,829.

Specification of Letters Patent.

Patented Dec. 5, 1911.

Application filed May 18, 1911. Serial No. 628,066.

To all whom it may concern:

Be it known that I, DE WILL G. VAUGHN, a citizen of the United States, residing at Richmond, in the county of Henrico and State of Virginia, have invented new and useful Improvements in Valve-Grinding Devices, of which the following is a specification.

This invention relates to valve grinding tools of a simple portable type designed to be manually operated for imparting an oscillating movement to the valve being ground; providing means for changing the position of the valve on its seat during the act of grinding without removing or disengaging the tool from the valve, and further providing means for engaging the tool and valve to insure a firm connection between the same should said tool be tilted intentionally or accidentally out of line with the axis of the valve.

To this end the invention consists of the novel construction, arrangement and combination of parts hereinafter described in detail and pointed out in the appended claims, reference being had to the accompanying drawings in which:—

Figure 1 is an elevation of the improved grinding tool in position for use. Fig. 2 a vertical central sectional view of the tool, and Fig. 3 is a detail view illustrating parts by which the position of the valve with relation to its seat may be changed during the grinding operation. Fig. 4 is a detail view partly in section illustrating the means for centering the bit.

In the drawing, the numeral 10 designates a cylindrical barrel on one end of which is secured a hand piece 11, in the present instance by means of a lug 12 on the lower end of the handle fitting into the barrel and fastened by a screw 13, any other means of fastening these parts together may be substituted if desired.

Slidably mounted within the barrel, preferably near its lower end, is a sleeve 14 formed with an internal screw thread or worm groove 15 engaging a worm 16 fixed on a shaft 17 extending longitudinally within the barrel 10 and projecting outwardly therefrom at its lower end for an indefinite distance. The upper end of the shaft 17 turns in a bearing in the lug 12 and

is held from endwise movement by any appropriate means, such as a screw 17a. Near its lower end the shaft 17 is reduced in diameter as at 18 for a purpose to be herein-after described.

Mounted to rotate in the hand piece 11 near its lower end is a transverse shaft 19 provided with a hand crank or other rotating means 20 on one end and a short crank 21 on its opposite end by means of which reciprocating motion is imparted to the sleeve 14 through a connecting rod 22 pivoted to said crank and to a screw, pin or the like 23 projecting from said sleeve through a slot 24 in the barrel 10.

Telescopically fitting over the lower end of the shaft 17 is a tubular extension 25 of any desired length provided with a bit 26 on its lower end for engaging a slot in the valve to be ground, and with a plurality of parallel longitudinal slots 27 on its upper end with any one of which a pin or key 28 on the shaft 17 is adapted to engage when the tubular extension 25 is slid upwardly on the shaft. A spring 29 within the tubular extension bears against the closed lower end thereof and against the end of the shaft 17 and normally holds the slotted end of said extension out of engagement with the pin or key 28. A screw or pin 30 projects from the tubular extension 25 into the reduced portion 18 of the shaft 17 and limits the endwise movement of the extension on said shaft, but permits free rotation of the same when disengaged from the pin or key 28 to change the position of the valve while being ground. For convenience in rotating the tubular extension 25, a collar 31 is mounted thereon and is here shown as held in place by the same screw 30 that projects into the reduced portion of the shaft 17.

The bit 26 is a thin plate pivoted centrally at 32 in a slot 33 cut in the lower end 95 of the sleeve 34 removably fastened by a screw or bolt 35 on the lower end of the tubular extension 25. Attached to the bit and projecting beyond its engaging edge is a stud 36 which enters a hole in the axial line 100 of the valve and centers the bit. The stud also assists in preventing said bit from slipping out of the receiving notch α in the valve.

In operation the valve to be ground is made with a slot in its upper face into which the bit 26 of the grinding tool is inserted, and the tool held in line with the axis of said valve. Pressure being applied to the hand grip, the shaft 17 is telescoped within the tubular extension 25, compressing the spring 29 and holding the valve with a yielding pressure against its seat. The downward telescopic movement of the shaft 17 brings the pin or key 28 into engagement with one of the notches 27 on the upper end of the tubular extension, thus locking these two parts together so that they will oscillate in unison. Now upon turning the hand crank 20 the sleeve 14, through the connections described, will be moved rectilinearly for a short distance, turning the shaft 17 through the worm connection with said sleeve a partial rotation in one direction and a similar movement in the opposite direction, thereby oscillating the valve in its seat and grinding the same. After a certain length of time the pressure imparted through the handpiece is relieved sufficiently to disengage the key from the notches 27 in the tubular extension, but not sufficiently to permit the bit to be removed or slipped off, or become disengaged from the valve, there being sufficient pressure to retain said bit in place. The tubular extension is now turned for a short distance, by grasping the collar 31 in the hand, for the purpose of changing the position of the valve with relation to its seat, after which the hand piece is again pressed down to cause engagement of the shaft 17 with the tubular extension and the grinding motion is continued. This motion is continued until the valve has been tightly ground into its seat, after which the tool is removed.

The bit 26 is pivotally mounted on the lower end of the tubular extension, and serves a very useful purpose, as it is well known that to hold the tool so that the shaft 17 will always be in line with the axis of the valve is a difficult matter, and should the bit be rigidly attached to the tubular extension any inclination given to the tool is liable to cause the bit to slip or jump from the notch in the valve, but by pivoting the bit on the tool these inclinations will not alter the position of the bit which will at all times remain firmly and squarely in the notch made in the valve to receive it. The upper ends of the septa or fingers between the notches 27 are preferably pointed as shown, so that when the shaft 17 is depressed it will cause the pin 28 to enter one of said notches and there will be no liability of said pin striking the top of said fingers and thereby fail to enter a notch.

This improved tool is simple and cheap in construction, strong and very efficient. By its use valves may be ground by hand with

ease and accuracy, and in places where it is impossible or difficult for power machines to operate.

Having thus described the invention what is claimed as new is:—

1. A valve grinding tool comprising an oscillating shaft, a worm on said shaft, a longitudinally movable sleeve co-operatively engaged with said worm to oscillate said shaft, a tubular extension telescopically and rotatably mounted on said shaft and provided with a bit, means for connecting said tubular extension to the shaft for oscillating the former when longitudinal pressure is applied to said shaft, and resilient means for disengaging said parts when released from pressure.

2. A valve grinding tool comprising a barrel, an oscillating shaft mounted longitudinally thereon, a worm on said shaft, a longitudinally movable sleeve co-operatively engaged with said worm to oscillate said shaft, a tubular extension telescopically mounted on said shaft and adapted to be rotated independently thereof, means for limiting the telescopic movement of said parts, a clutch device for connecting said tubular extension to the shaft for oscillating the extension when longitudinal pressure is applied to said shaft, resilient means for disengaging said parts when released from pressure, and a bit pivoted on the lower end of the tubular extension for engaging a valve to be ground.

3. A valve grinding tool comprising a barrel, a hand piece fixed on one end of said barrel, a longitudinal oscillating shaft in said barrel journaled in the hand piece, a worm on said shaft, a rectilinearly movable sleeve co-operatively engaged with said worm to oscillate the shaft, a crank shaft on the hand piece adapted to operate said sleeve, a tubular extension telescopically and rotatably mounted on said shaft, a swinging bit on said tubular extension, a clutch device for connecting said shaft and the tubular extension, and resilient means for disconnecting said clutch device.

4. A valve grinding tool comprising a two part telescopic shaft, said parts normally rotatable independently of each other, means for connecting said parts to oscillate in unison when telescoped by the application of pressure, a spring for partly separating said parts and disengaging said connection, a worm fixed on one part of said shaft, a bit pivotally connected to the other part, and rectilinearly movable means for oscillating said worm and its attached shaft.

5. A valve grinding tool comprising a two part telescopic shaft, said parts normally rotatable independently of each other, one of said parts having a plurality of parallel longitudinal slots in one end, the other part bearing a pin adapted to enter any one of

said slots under pressure to lock said parts together; a spring for disconnecting said parts, a worm fixed on one part of said shaft, a bit pivotally mounted in a sleeve detachably connected to the other part, and a rectilinearly movable sleeve cooperating with said worm for oscillating the same and the attached shaft.

In testimony whereof I have hereunto set my hand in presence of two subscribing witnesses.

DE WILL VAUGHN.
